ALFRED R. SWEARINGEN, OF MIAMI, FLORIDA, ASSIGNOR OF ONE-EIGHTH TO HELEN M. REARDON, OF MIAMI, FLORIDA, AND ONE-FOURTH TO ALBERT QUADOW, OF MIAMI, FLORIDA

TAILPIECE RETAINING MEANS

Application filed February 7, 1930. Serial No. 426,658.

This invention relates to certain refinements and improvements embodied in the construction of tailpieces of the type employed in association with stringed instruments, particularly of that family embodying the violin, viola, cello, and double bass.

It is a matter of common knowledge that the conventional tailpiece is of ebony or analogous material and constructed at the inner end with key-hole shaped openings for anchorage of the strings, and provided at the opposite ends with a gut loop which is engaged with a headed retention pin on the butt of the body of the instrument.

15 In its underside the tailpiece is formed adjacent the gut end with a pocket-like recess having a pair of spaced parallel bores for passage of the ends of the retaining gut and these ends are fastened in place in different manners. For instance by clamps, screws, knots, and wrapped threads.

The present invention relies for its novelty upon an improved and refined means for attaching the end portions of the gut loop 20 or noose to the anchored end of the tailpiece.

More specifically stated, the inventive conception involves the utilization of an appropriately shaped and constructed metal plate which is associated with the recess in 25 the underside of the tailpiece and constructed to permit the terminal ends of the anchoring gut to provide a dependable means and method of attaching said ends to the tailpiece.

30 In the drawings:

Figure 1 is a top plan view of a conventional violin showing the position of the tailpiece.

Figure 2 is a side view and a fragmentary 40 elevation showing the tailpiece embodying the features of this invention.

Figure 3 is a bottom plan view of the tailpiece embodying the features of this invention.

45 Figure 4 is a cross section on the line 4—4 of Figure 3.

Figure 5 is a longitudinal section on the line 5—5 of Figure 3.

50 Figure 6 is a perspective view of one of the types of gut fastening or retaining plates.

Figures 7, 8 and 9 are views showing modified types of plates.

Figure 10 is a top plan view of the end portion of the tailpiece and the association of the anchoring gut.

55 In the drawings, in Figure 2, the reference character 11 designates the body of a conventional violin, 12 the springs, 13 the tailpiece, 14 the looped anchoring gut, and 15 the headed retaining plug or pin on the butt 60 end of the body.

As seen in Figure 5, the tailpiece is formed with the customary recessed pocket 16 and the spaced parallel passages or bores 17 for the terminal ends 18 of the gut loop.

65 The gist of the invention, as before stated, is in the provision of the fastening plate which as shown in Figure 6 is generally designated by the numeral 19. It is preferably of flat form and pointed configuration and one end is doubled upon itself as indicated at 20 and terminates in a right-angularly disposed semi-circular guide and abutment 21. This abutment engages the shoulder in one end of the recess 16 as observed in Figure 5, and is constructed to permit the passage 70 of the ends 18 of the loops 14.

75 In the primary form of the invention, the edge portions of the plate are provided with wedge-shaped notches 22 in which the ends 80 of the gut are firmly fastened in an obvious manner. In this way the guide 21 abuts one end of the recess and the plate overlies the recess forming a cover therefor.

At this time, I call attention to Figures 7, 85 8 and 9 wherein diversified forms of the plate are shown. The plate 23 in Figure 7 is provided with a pair of holes 24 through which the terminal ends of the gut may be passed and knotted for secure fastening.

90 The plate 25 in Figure 8 is provided at its edge portion with semi-circular notches 26 in which the knotted ends (not shown) may be fastened.

95 The plate in Figure 9 is designated by the numeral 27 and is the same in construction except that it is provided with triangular holes 28 in which the unknotted ends may be wedged in an obvious manner.

100 A careful consideration of the description

in connection with the drawings will enable the reader to obtain a clear understanding of the construction and features and advantages of the invention. Therefore, a more ~~6~~ lengthy description is regarded unnecessary.

Minor changes in shape, size, materials and rearrangement of features coming within the field of invention claimed may be resorted to in actual practice if desired.

10 I claim:

1. In a stringed musical instrument accessory of the class described, a tailpiece provided at one end with a recess and spaced parallel communicating bores, an anchoring loop having its end portions passing forwardly through said bores and arranged in said recess a separate plate covering said recess and contacting with the underside of the adjacent portion of the tailpiece and provided with means for attachment of the terminal ends of said anchoring loop thereto.

2. As a new product of manufacture, a tailpiece accessory constructed for fastening the terminal ends of a gut loop to said tailpiece comprising a plate designed to cover the conventional recess in the underside of the tailpiece, one end of said plate being bent upon itself and formed with a terminal abutment, the body portion of the plate being provided with means for attachment of the terminal ends of said loop.

In testimony whereof I affix my signature.

ALFRED R. SWEARINGEN.
